UNITED STATES PATENT OFFICE.

SAMUEL L. HANSON, OF ALBERT LEA, MINNESOTA.

ADJUSTABLE CATTLE-STALL.

1,327,386.

Specification of Letters Patent.

Patented Jan. 6, 1920.

Application filed October 28, 1918. Serial No. 260,013.

To all whom it may concern:

Be it known that I, SAMUEL L. HANSON, a citizen of the United States, residing at Albert Lea, in the county of Freeborn and 5 State of Minnesota, have invented a new and useful Adjustable Cattle-Stall, of which the following is a specification.

This invention has reference to cattle stalls, and its object is to provide a stall 10 structure of simple and cheap construction which at the same time is particularly efficient, and is intended for use in connection with stanchions.

In accordance with the invention, the 15 stalls are provided at their forward ends with frames designed to receive and support stanchions, said frames being ordinarily one-piece structures, each separate from the other and erected on a suitable foundation, 20 while the stalls are divided one from the other by partition bars anchored at their rear ends and at their forward ends each connected to two adjacent stanchion supporting frames.

The partition bars stop short of the stanchion frames and connecting devices are provided for joining each partition bar to the adjacent portions of two stanchion frames, the connecting devices being so arranged 25 that they may be utilized for stalls of different widths.

The structure is of a character permitting it to be made of piping or rods, and fittings, all of which simplify the construction and 30 facilitate the erection and the repair of the stalls.

The invention will be best understood from a consideration of the following detailed description taken in connection with the accompanying drawing forming part of 35 this specification, with the understanding, however, that the invention is not confined to any strict conformity with the showing of the drawing but may be changed and modified so long as such changes and modifications mark no material departure from the salient features of the invention as expressed in the appended claims.

In the drawing:

Figure 1 is a perspective view of stanchion supporting frames with partition bars and connecting means from said bars to the stanchion frames.

Fig. 2 is a section on the line 2—2 of Fig. 1 but drawn on a larger scale.

Fig. 3 is a section on the line 3—3 of Fig. 2.

Fig. 4 is a section on the line 4—4 of Fig. 3.

Referring to the drawing, there is shown 60 in Fig. 1 a curb 1 located between an alleyway 2 and the floor 3 of the stall space. Erected at suitable intervals on the curb 1 are stanchion frames 4 which may be most conveniently made of metal pipe bent into 65 U-shape with the yoke or band 5 of the U uppermost and relatively level. The stanchion frames are shown as arranged in one upright plane.

Each frame 4 determines the head end of 70 the stall and the uprights of the adjacent frames are spaced apart a short distance. The purpose of the stanchion frames is to hold stanchions, but as the invention is not directed to either the construction of the 75 stanchions or the manner of securing them to the frames, a showing of the stanchions is omitted from the drawing. Erected on the floor 3 at a suitable distance back of the curb 1 are bars 6 rising at the rear directly 80 upward from the floor and then bent toward the space between two contiguous frames 4 and again rising as they approach the frames. The partition bars 6 are each in a plane perpendicular to the plane of the stanchion frames and to the plane of the floor. There is a partition bar 6 between each two adjacent stalls but as the bars are all alike there is but one complete partition bar 85 shown in the drawing. That end of the 90 partition bar adjacent to the frames 4 stops short of the frames and is joined to the frame uprights by a connecting structure capable of certain adjustments.

The connecting structure includes a clamp 95 or coupling structure 7 comprising two opposed bowed or partially cylindrical legs 8 projecting from a relative flat basic portion 9 and terminating at the ends remote from the base in ears 10 perforated for the 100 passage of a clamp bolt 11. The legs 8 are so shaped and spaced as to embrace a partition bar 6 when applied thereto and may be firmly held on the partition bar by tightening the bolt 11.

There are also provided two arms 12 and

13 of web and flange construction for lightness and strength, although capable of other construction. These two arms are curved lengthwise and terminate in flat ears 14 and 15, respectively, the ear 14 being shaped to engage flatwise against the basic portion 9 of the clamp 7 and the ear 15 is shaped to bear against the ear 14. The basic portion 9 of the clamp 7 has a recess 16 on the inner side of the leg or clamp side thereof and is flat on the outer side or face thereof, thus forming a broad bearing for the flat ear 14. The basic portion 9 and the ears 14 and 15 have matching perforations for the passage 10 of a clamp bolt 17 and about the perforation in the ear 15, there is formed a recess 18 to accommodate the nut of the bolt 17, as well as a tool (not shown) for removing said nut.

Those ends of the arms 12 and 13 remote 20 from the ears 14 and 15 each terminate in a clamp member 19 formed as part of the arm, and the corresponding end of the arm is recessed and shouldered to receive a matching clamp member 20 to embrace a corresponding upright 4 of a stanchion frame. A bolt 21 traversing the clamping end of the arm 12 or 13, as the case may be, and also the separate clamp member 20 serve to hold the arm 12 or 13, as the case may be, in firm 25 gripping relation to the upright of the frame 4 to which it is applied. The clamp members 19 and 20 and the bolt 21 constitute a coupling individual to the frames, and also to the separate connecting members 12 and 13.

With the bolt 11 loosened the clamp 7 is readily applied to the end of the bar 6 toward the stanchion frames and may be secured in any desired position of adjustment by tightening the bolt 11. The arms 12 and 13 are made fast to the clamp 8 by the bolt 17 and the arms may be spread or approached with relation to each other and finally clamped in the desired position by 45 tightening the bolt 17. The arms 12 and 13 are made fast to the side bars of the stanchion frames 4 by means of the clamp members 19 and 20 and bolts 21.

The connecting members may be all applied and temporarily tightened to a partial extent before the final adjustments are completed and when the desired adjustment of the parts is accomplished the bolts are drawn up tight, whereupon, the stalls will hold 55 their adjustment indefinitely.

The arms 12 and 13, because of the capability of approach or spread thereof, will readily accommodate two stanchion frames 4 spaced various distances apart and such 60 spacing is further accommodated by the adjustability of the clamp 8 lengthwise of the bar 6. The clamps at the ends of the arms 12 and 13 may be raised or lowered on the uprights of the frames 4, thus further facilitating the proper placing of the parti-

tion bars with relation to the stanchion frames in order to complete the stalls.

The structure is capable of manufacture and assembly from stock materials in most part. The partition bars and stanchion 70 frames may be made from commercial piping or commercial bars of stock sizes readily bent into the desired shapes. The clamp 7 and arms 12 and 13 together with the clamp members 20 are the only special fittings 75 needed. All the bolts may be of stock sizes.

The entire stall structure is of a character permitting it to be manufactured at a minimum cost and to be assembled at small expense for labor, while at the same time the 80 stall structure is particularly efficient and resistant to the action of cattle as well as possessing high sanitary qualities.

A narrow space or a wide space between the stanchion frame may be accommodated 85 by identically the same structure, the connecting parts readily accommodating themselves to different widths. The arms 12 and 13 also serve as guides directing cattle moving into the stalls so that they will naturally 90 project their heads through the stanchions instead of attempting to put their heads through some other parts of the forward ends of the stalls.

What is claimed is:—

1. In cattle stall construction embodying stanchion supporting frames spaced widthwise of the stalls, a partition bar for dividing one stall from another and approaching but stopping short of the plane of the frames, 100 and means for connecting the bar to adjacent stanchion supporting frames, comprising couplings individual to the frames, separate connecting members, one for each coupling, and a coupling structure common to the connecting members and to the partition bar with the combined length of the connecting members greater than the spacing of the supporting frames.

2. In cattle stall construction embodying spaced stanchion supporting frames, a partition bar for dividing one stall from another, and connections from the partition bar to the adjacent sides of the neighboring frames which connections gradually diverge 115 from the forward end of the partition bar to the respective frames.

3. In cattle stall construction, separate spaced inverted U-shaped stanchion supporting frames, and partition bars constituting 120 the sides of the stalls and having connections to the adjacent sides of neighboring frames, said connections being pivotally mounted on the partition bars and gradually diverging from each partition bar to the frames to 125 which they are connected.

4. In cattle stall construction embodying spaced stanchion supporting frames with adjacent upright sides, a partition bar for dividing one stall from another and stopping 130

short of the frames, and diverging connecting members both connected to the partition bar and each connected to a respective one of the upright side members of two adjacent frames.

5. In cattle stall construction embodying spaced stanchion supporting frames with adjacent upright sides, a partition bar for dividing one stall from another and stopping

10 short of the frames, and diverging connecting members both connected to the partition bar and each connected to a respective one of the upright side members of two adjacent frames, said connecting members being ad-

15 justable as to the spread of the ends connected to the frames, for different spacing of the frames, the divergence of said members guiding the heads of the animals into the stanchions as the animals move forward into

20 the stalls.

6. In cattle stall construction embodying spaced stanchion supporting frames arranged in one plane, a partition bar arranged in a plane perpendicular to the plane of the 25 frames and intermediate of two adjacent frames, and diverging members common to the bar and individual to the frames and adjustable as to height and spread with respect to the partition bar and frames, the combined length of the connecting members being greater than the spacing of two adjacent supporting frames from each other.

7. In stall construction, spaced adjacent U-shaped frames constituting the stanchion 35 supporting ends of the stalls, and division means between the stalls each comprising a partition bar rising toward the frames in a plane substantially perpendicular to the plane of the frames, and connections between 40 the division bar and the adjacent sides of the neighboring frames, comprising a clamp member for application to the end of the division bar toward the frames, curved arms

pivotaly connected together and to the clamp member, and coupling devices for connecting the arms to the adjacent upright members of the U-shaped frames.

8. In cattle stall construction, inverted U-shaped frames constituting the head ends of the stalls, partition bars constituting divisions between the stalls, and connections between each partition bar and the adjacent side members of neighboring frames, comprising curved arms each with an ear at one end overlapping the corresponding ear of the other arm, and at the other end provided with clamping means for engaging the adjacent uprights of the U-shaped frames, and a clamp structure for engaging the division bar and pivotally connected to the overlapping ears of the arms.

9. In cattle stall construction, inverted U-shaped frames constituting the head ends of the stalls, partition bars constituting divisions between the stalls, and connections between each partition bar and the adjacent side members of neighboring frames, comprising curved arms each with an ear at one end overlapping the corresponding ear of the other arm, and at the other end provided with clamping means for engaging the adjacent uprights of the U-shaped frames, and a clamp structure for engaging the division bar and pivotally connected to the overlapping ears of the arms, said arms being of web and flange construction and one arm having the ear at the end thereof provided with a recess to house the end portion of a bolt serving as the pivot connection between the ears.

In testimony that I claim the foregoing as my own, I have hereto affixed my signature.

SAMUEL L. HANSON.
